ELECTRIC HAIR CLIPPER

Erdick Nelson, Naperville, Ill.

Application February 2, 1954, Serial No. 28,791

Term of patent 14 years

(Cl. D22—3)

Fig. 1

Fig. 2

Fig. 3

Fig. 4

Fig. 1 is a top plan view of an electric hair clipper showing my new design;

Fig. 2 is a side elevational view thereof; the opposite side thereto being substantially similar in appearance;

Fig. 3 is a bottom plan view thereof; and

Fig. 4 is a rear end view thereof.

The essential features of my design reside in the portions shown in solid lines on the drawing.

I claim:

The ornamental design for an electric hair clipper, as shown and described.
